CLAIM

The ornamental design for a combined key ring, torch,
photograph holder and LCD watch, substantially as
shown and described.

DESCRIPTION

FIG. 1 is a front elevational view of a combined key
ring, torch, photograph holder and LCD watch, the
rear elevational view being a mirror image, showing
our new design;

FIG. 2 is a left side elevational view thereof;

FIG. 3 is a front elevational view showing the LCD
watch in a fully extended position thereof; and

FIG. 4 is a bottom plan view thereof;

FIG. 1

FIG. 2

FIG. 3

FIG. 4
